US0D1023046S

(12) **United States Design Patent** (10) **Patent No.:** **US D1,023,046 S**
(45) **Date of Patent:** **** Apr. 16, 2024**

(54) **DISPLAY SCREEN OR PORTION THEREOF
WITH GRAPHICAL USER INTERFACE**

(71) Applicant: **HUAWEI TECHNOLOGIES CO., LTD.**, Guangdong (CN)

(72) Inventor: **Minhao Li**, Shanghai (CN)

(73) Assignee: **HUAWEI TECHNOLOGIES CO., LTD.**, Shenzhen (CN)

(**) Term: **15 Years**

(21) Appl. No.: **29/843,003**

(22) Filed: **Jun. 17, 2022**

(30) **Foreign Application Priority Data**

Dec. 21, 2021 (CN) 202130844574.8

(57) **CLAIM**

The ornamental design for a display screen or portion thereof with graphical user interface, as shown and described.

DESCRIPTION

The FIGURE is a front view of a display screen or portion thereof with a graphical user interface showing my new design.

The outermost dash-dot broken lines in the drawings illustrate the display screen or portion thereof and form no part of the claimed design. The other dotted broken lines in the drawings illustrate portions of the graphical user interface that form no part of the claimed design.

1 Claim, 1 Drawing Sheet
